HENRY L. GOTTESBUREN AND JOHN P. JOYCE, OF KANSAS CITY, KANSAS.

SANITARY BUILT-IN CLEAN-OUT.

Application filed February 23, 1924. Serial No. 394,476.

The invention relates to an improved sanitary built-in clean out for continuous vent and waste pipes, for lavatories, sinks, urinals and the like.

5 Waste pipes from lavatories, sinks, urinals and the like frequently become obstructed with foreign matter, flooding the room in which they are located with water.

The usual method of cleaning the waste 10 pipe is to apply water or air pressure and attempt to force the foreign matter through the pipe, but there is less resistance in the vent pipe than in the waste pipe and the air or water is forced up the vent pipe 15 and fails to remove the obstruction.

As plumbing has heretofore been installed it has been found impossible to pass anything as a wire through the pipe owing to the impossibility of disconnecting the pipe 20 at a point that will admit of passing a wire or the like into the pipe.

The present invention has provided an improved built in clean out for continuous vent and waste pipes which may be opened 25 and a wire or the like passed up the vent pipe and down the waste so that any foreign matter which may obstruct the pipe may be forced therethrough.

With these and other objects in view, the 30 invention consists in the features of construction, combinations and arrangements of parts hereinafter set forth and more particularly pointed out in the appended claims, the accompanying drawings illustrating a 35 form of the sanitary built in clean out.

In the drawings:-

Fig. 1 is a fragmentary plan view of a building showing a portion of one wall which is broken away to illustrate the location 40 of the vent pipe, ordinary fixtures in the building are also shown.

Fig. 2 is a vertical section taken on line 2-2 of Fig. 1, with certain parts shown in full view.

45 Fig. 3 is a fragmentary view of Fig. 2 with certain parts shown in sectional view that are shown in full view in Fig. 2 owing to the reduced scale of Fig. 2.

Fig. 4 is a sectional view taken on line 50 4-4 of Fig. 2 and is the same scale as the latter figure.

The floor 1, wall 2, bath tub 3, wash basin 4, drum trap 5, drum trap lid 6, washbasin trap 8, branch waste pipe 9, vent pipe 10,

55 T shaped connection 11, and waste pipe 12 and 12^a are all of common and well known

construction and shown merely to illustrate the use of the improved sanitary built-in clean out; it being understood that the vent pipe 10 and waste pipe 12 and 12^a form a 60 continuous vent and waste pipe.

The improved T shaped fitting 13 is located within the wall 2 and connected to the waste pipe 12 and 12^a and provided with the removable plug 14 which is accessible 65 through the opening formed by the frame 15 built in the wall 2, by removing the cover plate 16 which is secured in closed position by the screws 17.

The T shaped fitting 13 is provided with 70 the shoulders 18 and 19 which the upwardly extending section 12 and the downwardly extending section 12^a of the waste pipe respectively abut, so that there is no obstruction to prevent the passing of a wire 75 through the opening 20 and through the vent pipe 10 or the waste pipe 12 and 12^a when the plug 14 is removed.

When the branch waste pipe 9, or the waste pipe 12 and 12^a become obstructed, 80 the usual method is to apply water or air pressure to the end 21 of the branch pipe 9 within the basin 4, which usually forces the obstruction upwardly into the vent pipe 10 or downwardly into the waste pipe 12 and 12^a. In either case it is often necessary to remove a portion of the wall 2 and remove the pipe in order to remove the obstruction.

With the improved sanitary built-in clean 85 out it is only necessary to remove the cover plate 16 and the plug 14 and pass any instrument as a wire, flexible rod, or flexible tube or the like upwardly through the vent pipe 10 and downwardly through the waste pipe 12 and 12^a. In either case the obstruction 90 may be forced through the pipe.

The improved sanitary built-in clean out reduces the cost of plumbing bills and obviates the usual subsequent carpentering, 100 plastering and repapering bills, as it eliminates the tearing open of the wall and the removal of the pipes.

Having described our invention, what we 105 claim as new, and desire to secure by Letters Patent, is:-

1. In household plumbing, the combination of a hollow wall having an opening communicating with the hollow thereof, an upright waste pipe within the wall, a branch waste pipe entering the wall and connected with the upright waste pipe, a T 110 in the upright waste pipe, a short boss on

the T having a large bore opposite the opening in the wall and a removable closure for the boss within the wall.

2. In household plumbing, a hollow wall having an opening communicating with the hollow therein, a removable cover plate closing said opening, a waste pipe within the hollow of the wall, a branch waste pipe entering the wall above the opening and connected with the waste pipe, a vent pipe leading upwardly from the waste pipe, a T in the waste pipe having a lateral opening opposite the cover plate and a removable closure for said lateral opening behind the removable cover plate.

3. In household plumbing, the combination of a hollow wall having an opening communicating with the hollow therein, a removable cover plate closing said opening,

an upright pipe enclosed within the hollow wall, a drain entering the wall adjacent to the opening and connected with the pipe, a T in the pipe presenting a large opening opposite the opening in the wall and a removable closure for said T wholly within the wall.

4. In household plumbing, the combination of a hollow wall having an opening communicating with the hollow, a removable cover plate for said opening, a pipe enclosed within the hollow wall, a drain entering the wall adjacent to the opening in the wall and connected with said pipe, a T in said pipe having a lateral opening opposite the cover plate and a removable closure for said lateral opening.
